UNITED STATES PATENT OFFICE

2,236,886

SINK STRAINER AND STOPPER AND
THE LIKE

Roy H. Zinkil, Oak Park, and Eugene W. Marchand, Jr., Maywood, Ill., assignors to Crane Co., Chicago, Ill., a corporation of Illinois

Original application June 17, 1938, Serial No. 214,200. Divided and this application October 14, 1939, Serial No. 299,516

4 Claims. (Cl. 4—287)

More particularly, our invention relates to a more simple and economical sink strainer and stopper combination than heretofore available for the purpose set forth, in which the latter member is preferably embodied in basket or tubular form with one end perforated for straining purposes and in which a suitable plug or stopper member carried by the strainer or basket is reciprocably movable therewithin so as to serve as a valve shut-off enabling the filling of the basin of the sink with water, if desired. This application is a division of our original application Serial No. 214,200 filed June 17, 1938.

Sink strainers of a previous type have been available in which the valve has been removable as an integral part of the strainer and in which the stopper member mounted in the strainer has been reciprocably movable upon similar movement by the handle, but to our knowledge no one has employed a construction in which upon the combination of reciprocating and pivotal movement of the stopper handle the latter member is so actuated to be positioned close to the top or rim of the basket strainer whether the valve is in open or closed position, thus clearly avoiding the usual deposits within the strainer.

Another important advantage lies in providing toggle action in a jointed handle whereby the plug or closure member may be suitably locked.

Another advantage lies in providing a T handle form of construction in which the latter may be actuated with great convenience.

A further object lies in providing for a strainer and a valve closure member in which the latter member may be removed either individually for ready replacement or inspection or while assembled with the basket strainer, the removability being facilitated by the disengagement of the valve handle allowing for the strainer to be lifted without disturbing the positioning of the valve proper.

Other advantages of the construction will become more readily apparent in connection with a review of the patent drawing as described in the following figures:

Fig. 1 is a sectional assembly view of an embodiment of our invention showing the preferred embodiment of the construction in which a jointed or toggle mounted lever handle is used to lock or hold the plug or closure member in an open position upon the strainer.

Fig. 2 is a fragmentary plan view of the same construction.

Fig. 3 is a view similar to Fig. 1 except that

the plug or stopper is shown in the closed position.

Similar reference characters refer to like parts throughout the various views.

Referring to Fig. 1, the numeral 1 refers to a sink structure provided with the usual enamel coating 2 and having a drain opening 3 within which a conventional spud member 4 is applied, having one portion threaded as at 5, the lower portion of the sink at 6 having an abutting surface against which the gasket member 7 is positioned. A locking nut 8 is threadedly mounted upon the threads 5 of the spud member 4 in order to hold the latter in position within the sink drain opening 3 and also to make a watertight joint preventing leakage past the periphery of the spud member within the sink opening proper. The lower portion of the spud, as at 9, is preferably tapered and provided at its extreme lower portion with threads 11 by means of which the usual connection is made to a pipe and trap (not shown). A conventional spider 12 is used therein to prevent relatively large particles from dropping through and into the sink discharge trap (not shown).

Resting upon the peripheral shoulder 13 therewithin, a basket type of strainer 14 is mounted, the sides of which may be made solid, as indicated, or perforated, and the lower portion, as at 15, is preferably perforated to serve as a strainer. The strainer 14 at its center portion is provided with a hub 16 within which a valve member and jointed or pivotal lever 17 are reciprocably journaled, the handle preferably being of cylindrical form and having a T connection 18 at its upper end and pivotally attached, as at 19, to a complementary cylindrical form 21 journaled snugly within the hub 16 and preferably an integral part of the valve or stopper member 22, having a finished seat portion 23 for engagement with a similar surface or seat 24 upon the spud 4. Thus it will be apparent that by simply placing the lever 17 in a vertical position the stop end 25 may then be moved interiorly within the bearing of the hub 16 so that the lever 17 is then in axial alignment with the lower portion 21. This will enable the entire valve structure and handle to be dropped by its own weight against the seat 24 and thus close the drain opening when desired.

It will be further apparent that upon gripping the T extension 18, the valve 22 may be lifted from the seat 24 and, if desired, the entire basket strainer 14 may be removed simultaneously with the closure member 22, or if it is desired to drain

the water, then the handle may simply be lifted sufficiently so that the stopper 25 contacts as at 10, shown in Fig. 1, thereby holding the valve closure member in the open position.

It should be noted that at all times the end of the handle 17 is positioned sufficiently above the lower and interior portion of the basket type strainer so that it is unnecessary to have the fingers contact with the material accumulated within the strainer proper, and if desired further, the T connection 18 may be dispensed with entirely, in which case the basket type strainer may be slipped over the cylindrical portion of the handle 17 without disturbing the positioning of the valve 22. Obviously, of course, if it is desired to retain the T connection 18, the pin 19 may readily be made removable for the purpose of disjointing the handle thereby providing for the independent removal of the basket type strainer.

Having thus described our invention what we claim and desire to secure by Letters Patent is:

1. In a combined sink strainer and stopper arrangement, a tubular member secured within the drain opening of a sink or the like, a stopper serving as a shut-off for the said drain opening and seating in the lower end of the said tubular member, a substantially cylindrically formed strainer adapted to be positioned loosely within the said tubular member, an actuating handle for the said stopper member, guide means for the stopper projecting upwardly within the strainer, said handle being pivotally movable upon an upper portion of the said guide means, whereby upon pivotable movement of the said handle to a position in substantial axial alignment with said guide means the said stopper member is rendered reciprocably movable relative to the said strainer.

2. The combination of a sink strainer and stopper including a hollow spud member and a cupped strainer adapted to be positioned within the drain opening of a sink or the like, a reciprocably operable plug for the said drain opening, the said

hollow spud member providing a seat for the said plug, a demountably attached pivotable operating handle for the said plug, whereby upon disengagement of the said handle from its pivotable attachment with the said plug the said strainer may be removed without displacement of the said plug from the said seat.

3. In a combined sink strainer and plug arrangement, a hollow spud member secured within the drain opening of a sink or the like and providing a seat for the said plug, a cupped strainer adapted to be removably positioned loosely within the said spud member and with an elongated guide boss extending wholly within the strainer, the said plug being positioned below the said strainer and being reciprocably operable by a pivotable handle extending through a suitable aperture in the guide boss of the said strainer, whereby upon lifting the plug and angularly positioning an end portion of the said handle upon an upper surface of the said guide boss the said plug will be retained in a flow-permitting position.

4. In a combined sink strainer and plug arrangement, a hollow spud member secured within the drain opening of a sink or the like and providing a seat for the said plug, a cupped strainer adapted to be removably positioned within the said spud member, the said plug being positioned below and outside of the said strainer and being reciprocably operable by a pivotably movable handle, the latter when in its vertical position being extendible through a suitable aperture communicating with the cupped portion of the said strainer, the said plug having an extended portion journaled within the aperture of the said strainer, the said extended portion forming a substantially unbroken guide means within the aperture and between the said handle and the said plug when the latter member is moved from open to closed position and vice versa.
